SHORING DEVICE

Francis A. Poole, of Cleveland, Ohio

Application August 13, 1928, Serial No. 299,243
Renewed December 2, 1932

14 Claims. (Cl. 254—100)

My invention relates to shoring devices, and more particularly to an adjustable shore or prop for temporarily supporting or bracing walls, floors, scaffolds, false frame-work and the like. It is especially useful in connection with the erection of buildings and other structures made of concrete, or other materials where a knockdown frame-work or temporary scaffolding is employed. As designed and constructed the device permits both wide and close adjustments to be made quickly and easily, and provides a strong prop and stable support for such loads as it is designed to carry, all without danger of yielding, slipping or telescoping. The strength of this shoring device and its mode and range of adjustment is such that it can be used to take up or compensate for the settling that usually occurs when the shore or prop is supported on loose earth or on a poor foundation, or when an additional weight or great stress is applied. The present device may also be used to support a scaffold platform and to elevate the materials or occupants carried thereby. The device may also be used for bracing and shoring the walls of trenches or excavations of various widths, or as a jack or lifting implement. Accordingly, I do not wish to limit myself to the uses to which the device may be applied, nor to minute or exact details of construction, though showing and exemplifying a preferred embodiment of the invention in the accompanying drawing. Thus Fig. 1 is a front view, and Fig. 2 is a side elevation of one of my improved shoring devices. Fig. 3 is a sectional view of the working parts, and Fig. 4 a sectional view and side elevation, showing said parts in position to raise the cranking device. Fig. 5 is a side elevation of the locking pin. Fig. 6 is a perspective view of the operating mechanism. Figs. 7 and 8 are sectional views on lines 7—7 and 8—8 of Fig. 3 and Fig. 4 respectively.

The invention comprises a hollow column or tubular member A, an extensible member B telescoped within one end of column A, a pair of co-operating power-transmitting devices C and D for producing relative movement between the telescopic members A and B, and a shiftable locking element E for fastening the devices C and D alternatively to base member A. As shown herein member A is a tubular metal column of angular cross section, having a flanged base part 2 to support it in an upright position or against a wall. A slot or opening divides one side wall of member A lengthwise into two parts or flanges 4—4 which are provided with paired perforations 5—5 at uniformly spaced intervals substantially the full length of the column. In the present instance a sheet of metal is bent into the desired hollow angular shape with a single longitudinal slot or opening at one side, but it should be understood that this hollow column may be made or fabri-

cated of separate pieces of angle iron or channelled stock assembled to serve a like purpose. Also, column A may be circular or of pipe formation and slotted lengthwise. In the present instance the longitudinal slot or opening 3 splits member A 65 its full length, but the flanged base 2 ties the divided walls together at one end while the opposite end is tied and reinforced by a band 6.

Extensible member B may consist of a solid wooden beam or squared piece of timber, as shown in Fig. 3, or it may be used as the extensible member, as illustrated in Fig. 4. In either case it telescopes or projects into hollow member A and is detachably fastened to one of the power-operating devices, preferably to the square head 7 of 75 the lift or push member D. Head 7 is flanged to embrace or socket the inner end of member B, and a screw, nail or bolt 8 secures the beam thereto. In using the pipe B its end is seated within a circular channel b in the top of head 7. 80

A screw-headed shaft or stem 9 is affixed to or forms an integral part of head 7, and this shaft extends through a yoke portion 12 of device C and also through a rotatable nut 10 which forms part of a mitre or bevelgear 11 mounted within 85 or upon device C. Ball or roller bearings 14 are employed to take up the thrust of nut 10, when designed for heavy loads, but such bearings are omitted in a shore designed for light loads. Power is applied to gear 11 and nut 10 by a second 90 bevel gear or pinion 15 on a short transverse shaft 16 which projects outwardly through the longitudinal slot or opening 3 where a crank handle 17 may be connected therewith to rotate the gears and nut. Such cranking imparts a longitudinal 95 movement to screw shaft 9, assuming the mounting C for the cranking mechanism is locked in a stationary position within column or hollow member A.

Locking of device C is effected by element E 100 which is of U-shape or bifurcated to span slot 3 and project through the paired perforations 5—5 in flanges 4—4 of column A, it being further understood that corresponding openings are provided in the body of device C and in the opposite 105 wall of column A to receive the bifurcated portions of locking element E, see Figs. 3 and 7. A squared foot portion 18 is connected by a reduced neck 19 to the central body portion of the device C, and chamber 20 within the neck 19 provides a 110 closed space for screw shaft 9 to travel in and to hold a lubricant for the shaft. The bottom of foot portion 18 is provided with a circular groove to permit a beam, or a pipe to be secured thereto, reference being had to the duplicate arrangement 115 at the opposite end or head 7 of the device for connecting a beam B or pipe B' thereto as herein before described.

Assuming column A is to be used in an upright position it is placed at rest upon a seating sur- 120

face, and then the inner member B and the cranking devices C and D are jointly raised until the outer end of the member is placed in contact with or closely adjacent to the wall, joist, beam, or platform F to be engaged or supported. Locking element E is then introduced into the perforations in column A and passed through the transverse openings in the body portions of device C, thereby locking this part to the column. Rotation of the crank handle then operates the gears and nut and shifts the screw shaft and device D longitudinally within column A until the shoring movement is accomplished, or until the maximum travel of the screw shaft relatively to device C occurs.

If the travel of the screw is not sufficient to carry the shoring member or prop B against the parts to be engaged and supported, a second locking element E' is introduced into the perforated flanges and through head 7 of device D to lock the same to column A. Locking element E is then withdrawn from device C, and a reverse rotative movement given to the crank handle, which causes the nut to travel upwardly on the screw-shaft (now held in a stationary position in the column) thereby raising the cranking mechanism bodily within column A, thus locking this device again in a stationary position on the column for uplift or push movement of device D and member B whenever the second locking element E' is removed. A wide range of adjustment of the cranking mechanism and member B is afforded within column A without actuating the cranking mechanism, and then when the parts are locked as stated a more limited adjustment with power applied to the nut and screw shaft is available to either jamb the shoring appliance in position, to apply an expanding pressure, or to lift a load.

What I claim is:

1. A shoring device, comprising a pair of telescopic members, a power device including a pair of co-operating members for effecting a spreading movement between said telescopic members, and means for locking said pair of power device members alternatively at different places longitudinally to one of said telescopic members.

2. A shoring device, comprising a pair of extensible members, a pair of co-operating power-transmitting devices for producing extensible movements between said members, and means for alternatively locking each of said power devices adjustably to one of said extensible members.

3. A shoring device, comprising a pair of extensible members, in combination with a jack having a body movable lengthwise of one member, and an extensible head engageable with the other member, and means for locking the jack body and the jack head alternatively to said first member.

4. A shoring device, comprising a pair of telescopic members, a screw jack having a body slidably mounted within one member and including a push member engaging the other member, and means for locking said body and push member alternatively at different places lengthwise of one of said telescopic members.

5. A shoring device, comprising a tubular column; an extensible member; a push element connected to said member; operating means for said push element, including a mounting shiftable lengthwise of said column; and means for locking said push element of said mounting alternatively to said column.

6. A shoring device, comprising a tubular column having a slot lengthwise thereof and perforations in its side walls, an extensible member extending into said column, a jack body mounted

to slide within said column, means for locking said jack body to said column where perforated, and jack-mechanism mounted upon said jack body having an extensible head including means for locking said head to said column where perforated and an operating part extending through said slot in the column.

7. A shoring device, comprising a slotted column, an extensible member telescoped within said column, a screw-jack including a body slidably confined within said column and a push member connected with said body, operating means for said push member engageable at said slot, and a device for locking either said body or said push member alternatively at spaced intervals lengthwise of said column.

8. A shoring device, comprising a hollow column, an extensible member in telescopic connection with said column, a jack screw engageable with the inner end of said member, a jack body slidably mounted within said column carrying gearing and a nut engaged with said screw, means for securing either said jack body or said screw to said column, and means for rotating said gearing either to move the jack body or the screw relatively to the column.

9. A shoring device, comprising a hollow slotted column, an extensible member within said column, a jack body and lift screw having a head engaging said extensible member and the walls of said column to prevent turning movements therein, a rotatable nut and gearing mounted upon said jack body to operate said lift screw, operating means extending through the slot in said column to rotate said gearing, and means for locking either said jack body or screw head to said column alternatively.

10. A shoring device, including a perforated column, a jack body slidably mounted within said column, having perforations, a perforated lift member and gearing carried by said jack body, and locking devices adapted to be removably inserted within the perforations in said column and alternatively in the perforations in either said jack body or said lift member.

11. A shoring device, including a slotted column having spaced perforations bordering the slot therein, a jack slidably confined within said body, and a removable bifurcated element adapted to lock said jack in a stationary position upon said column where perforated, said element spanning the slot and connecting the divided portions of the column.

12. A shoring device, including a hollow column, a jack body carrying a jack screw and screw operating devices, and locking devices for alternatively securing either said screw or jack body immovably to said column.

13. A shoring device, comprising a pair of extensible members, a jack having a body slidably related to one of said extensible members and including a push element engageable with said other extensible member, and means for securing said jack member and push element alternatively at different places lengthwise of said first extensible member.

14. A shoring device including a hollow slotted column, a jack body mounted to slide within said column, means for locking said body to the column at spaced intervals longitudinally thereof, a jack screw carried by said body having a head, means for locking said head to said column at spaced intervals, and means for securing an extensible member to said head.
